UNITED STATES PATENT OFFICE.

EDWARD JACOB PRATT, OF NEW YORK, N. Y., ASSIGNOR TO WESTERN ELECTRIC COMPANY, INCORPORATED, OF NEW YORK, N. Y., A CORPORATION OF NEW YORK.

RELAY.

Application filed September 9, 1924. Serial No. 736,693.

To all whom it may concern:

Be it known that I, EDWARD JACOB PRATT, a citizen of the United States of America, residing at New York, in the county of New York, State of New York, have invented certain new and useful Improvements in Relays, of which the following is a full, clear, concise, and exact description.

This invention relates to relays, and more particularly to alternating current relays for controlling electrical circuits.

The object of this invention is to provide an improved relay of this character, wherein the energization of a coil or a plurality of coils positioned in a magnetic field, serves to actuate an armature having an associated loose contact device which in turn controls a circuit arrangement.

A feature of the invention resides in the provision of a cross pole magnetic structure similar to that disclosed in a copending application, Serial No. 678,935, filed December 6, 1923, each pole of which is provided with two polar extensions projecting on opposite sides of each pole, which in effect form two sets of north and south poles; one set of north and south polar extensions being positioned oppositely to the other set. Rigidly positioned between these polar extensions is a coil adapted to be connected to a source of alternating current. An adjustable reed armature passes through the center of the coil and supports one end of a loose contact device similar to that shown in copending application, Serial No. 715,002, filed May 22, 1924. When the coil is energized by alternating current, it causes the loose contact device to open its contacts which may control a local circuit.

Another feature of the invention resides in the provision of a relay having a plurality of coils, one being located in each of the branches of an alternating current flux circuit and arranged, when energized by alternating current, to actuate a reed armature in accordance with the frequency of the applied alternating current. The motion of said reed armature is utilized to operate a loose contact device similar to that previously mentioned which in turn may control an electrical circuit.

These and numerous other features of this invention may be understood from the following description and the accompanying drawing, Fig. 1 of which represents a relay

embodimenting the invention with the coil and polar structure partly in cross-section. Figs. 2 and 3 are different views of the same relay to indicate structural details not apparent in Fig. 1. Similar components of the relay are similarly marked in the different figures. Fig. 4 is a perspective of the cross pole construction employed in the relay.

Referring to the drawings, 1 represents the mounting base to which is suitably attached as by screws 2, all necessary mounting posts 3 and terminals 4, and holding plate 5. The mounting base may be of micarta or similar insulating material. Holding plate 5 serves as a base to which is attached relay base 6 by means of angle brackets 7 and 8. Suitably attached to the under side of relay base 6 by details 10 and 11 is a U-shaped magnet 9. A detailed description of the magnetic, polar and contact structures on the upper side of relay base 6 will now be given. To support 12 mounted on base 6 is rigidly attached one extremity of reed armature 13. The effective vibrating length of armature 12 is minutely controlled by adjustable clamping means consisting of a base 14 and top 15. Clamping top 15 is suitably niched so that reed 15 snugly fits between the under side of clamping top 15 and the upper side of 14. Slots 16 are provided in base 6 through which screws 17 pass to hold the adjustable base 14 in any desired position. When 14 is moved to a desired position and the screws 17 tightened, reed 13 is clamped to relay base 6. The effective length of the reed or armature will therefore comprise the portion thereof between the clamping point and the other extremity extending between poles 18, 19, 20, 21 and through coil 22. Proceeding to a consideration of the cross pole construction as illustrated in Fig. 4, N and S represent respective north and south polar extremities of magnet 9. To each pole is connected two polar extensions, as 19 and 20 to pole N, and 18 and 21 to pole S. The result in effect is tantamount to producing two north poles 19 and 20, and two south poles 18 and 21. The extensions are affixed to the poles by screws 23 or in any other suitable manner. Coil 22 has a central opening, is positioned between the polar extensions, and is supported at its center portion by prongs 24 of the polar extensions in such

a manner as to prevent it from interfering with the vibration of armature 13 which projects therethrough. Considering the loose contact device, 26 is a right-angled support member affixed to the armature. The upright portion of the support 26 is apertured and loosely supports one extremity of the tubular contact device 27. The other end of contact device 27 is in the form of a hook eye which is linked with a similar hook eye 28 which is rigidly held by mounting 29, itself securely fastened to base 6. These extremities of contact device 27 and terminal 28 may be compared in their contact relation to two links of a chain the upper link of which supports the lower one.

It may be noted that polar extensions 18, 19, 20, and 21 may be adjustably moved by loosening screws 23 to vary the position of the extensions by moving them as desired in slotted spaces 35. Upon adjusting them to suitably fix the space relation between oppositely positioned prongs 24, and the armature, they may then be clamped in the desired position by tightening screws 23. The strength of the flux circuits between the two sets of poles can therefore be easily and minutely varied, to vary the vibration of the reed.

30 The operation of this relay will now be explained. Upon the energization of coil 22 by a source of alternating current, reed or armature 13 will be actuated and commence to vibrate, the coil being located over the working air gaps, that is, at the junction of the two branches of the alternating current flux circuit in accordance with the two sets of poles provided in the polar structure. The reed may, as hereinbefore explained, be controlled to vibrate in accordance with the frequency of the applied current. Assuming that contact device 27 normally closes a circuit by being in loose contact at its extremities with support 26 and terminals 28, the vibration of the reed will cause vibration of the contact device and break such a normally closed circuit at one or both of these contacts. The control of any circuit in which contact device 27 is a link, could therefore be had by such a relay. Upon the deenergization of coil 22, the armature ceases vibrating, and contact device 27, by force of gravity will thereupon close its contacts, and the normally closed circuit is once more completed.

It is, of course, apparent that the relay could, in this manner, control any desired circuit arrangement.

Proceeding to a consideration of the relay illustrated in Figs. 5, 6 and 7, the mounting base 1, mounting post 3, terminals 4, holding plate 5, relay base 6, angle brackets 7 and 8 and U-shaped magnet 9 are in structure and position substantially as described in connection with Figs. 1, 2, and 3. A

detailed description of the magnetic, polar and contact structures on the upper side of relay base 6 will now be given. To support 12, is rigidly attached one extremity of armature or reed 13 by means of screw 14. Support 12 is welded or otherwise suitably held to base 6. The effective vibrating length of reed 13 is controlled by adjustment means 15. The position of bottom portion 6, of adjustment means 15, may be variably controlled by screw jack 17 which is itself rotated by knob 18, to effect such motion. Both top and bottom portions of adjustment means 15 are slotted as illustrated by orifices 19, which extend the total depth of device 15. By moving knob 18, therefore, means 15 may be variously positioned and upon being clamped by screws 20 will fix the length of reed 13 to enable its vibration in accordance with any desired frequency. Reed 13 is channeled, and fits into the top portion of adjustment means 15, serving to keep the means in alignment with the reed to prevent distortion of the reed upon its being clamped in position.

Referring to the magnetic and polar structure, 21 and 22 are projection arms of suitable magnetic material clamped between the polar extremities of magnet 9 and base 6. Topmost extremities of projections 21 and 22 are fastened by screws to cross member 23. It should be noted that base 6 and cross member 23 are of non-magnetic material, for example, brass. To the inner sides of projections 21 and 22 are fastened arms 24 to which coils 25 are secured. Arms 24 extend beneath coils 25 and have their extremities 26 in space relation with cores 27 of the coils, so that the extremity of reed 13 terminates intermediate the cores and the extremities 26. The cores 27 are joined at 28 to the projections of the magnets 21 and 22, thereby completing the magnetic circuit at this joint. Coils 25 are preferably serially connected and arranged to be energized by a source of alternating current, not shown. The contact device employed in this relay is substantially as described hereinbefore in connection with Figs. 1, 2, and 3. The contact member 30 is supported at one extremity by right-angled support 31, affixed to reed 13. The other extremity is loosely linked, as hereinbefore described to hooked terminal 32 which is rigidly fixed to mounting 33, itself securely fastened to base 6. 34 represents a terminal on mounting 33 to make electrical connection with an outside conductor.

The operation of the relay is as follows: Upon the energization of coils 25, reed 13 will vibrate in accordance with the frequency of the applied current. To strengthen the flux current, by decreasing the gaps between cores 27 and extremities 26, screw knobs 36 controlled by nuts 37 may vari-

- ably apply pressure on the cores or extremities to narrow the gap therebetween. Inasmuch as knobs 36 are of non-magnetic material, the course of the flux circuit is not affected thereby. Upon the vibration of the reed contact device 30 will accordingly vibrate, and break its contacts with terminal 32 and support 31. If contact device 30 be assumed to normally close a circuit at said contacts, its action would tend to break the circuit at the contacts. When the coils are deenergized, the reed will cease vibrating and the intermittent breaking of the circuit due to the vibration of the reed will accordingly stop. The electrical continuity of the circuit will thus be restored by the contact device due to the force of gravity, removing contact at its extremities.
- 10 It may be noted that the reed is apertured as shown at 40 beneath the contact device 30, to make it lighter in weight and prevent possible interference from waves set up during vibration.
- 15 It is a matter of note that when the free end of the armature or reed is adjusted so that its mechanical period of vibration is the same as the period of the alternating current through the energizing coil or coils, the armature will vibrate with the maximum amplitude. When the amplitude is such that its acceleration just exceeds that of gravity, the contacts will open, effect the operation of the relay, and control the circuit dependent for its continuity upon the normal condition of the relay. Since the amplitude required at the voice frequency is very small, this device is sensitive to extremely small alternating currents. Further, it is apparent that the contacting device is free to move upon the slightest vibration imparted to it through the supporting contacts. No friction or binding is present which would require greater amplitudes of motion to break the steady contacts obtained when the device is at rest.

What is claimed is:

1. An electromagnetic device comprising a magnet having two north and two south polar extensions forming two sets of north and south poles, a coil positioned between said polar extensions, an armature extending between said polar extensions and through said coil, and a contact device loosely supported at one end from said armature.
2. An electromagnetic device comprising a magnet having two north and two south polar extensions forming two sets of north and south poles, a coil positioned between said polar extensions, an armature extending through said coil and adapted to be actuated upon the energization of said coil by a source of alternating current, said armature being in spaced relation to said coil and said polar extensions, and a contact device loosely supported at one end from said armature.
3. An electromagnetic device comprising a magnet having polar extensions forming two sets of north and south poles, an armature positioned intermediate said two sets of poles, a contact device loosely resting upon and normally connecting a plurality of terminals, one of which terminals is mounted on said armature, and means comprising a coil positioned between said sets of poles adapted when energized by a source of alternating current to vibrate said armature to break said electrical connections of said device.
4. An electromagnetic device comprising an armature, a magnet having a plurality of polar extensions concentrated at opposite sides of said armature, two of said polar extensions on one side being of opposite polarity, two of said polar extensions on the other side being of opposite polarity, each individual one of said polar extensions being directly opposite a polar extension of the opposite polarity, an alternating current winding cooperating with said armature, and a contact device loosely engaging and electrically connecting a plurality of terminals, one of which is mounted on said armature, whereby upon the energization of said winding, said armature causes said contact device to vibrate, thereby breaking the connection between said terminals.
5. An electromagnetic device comprising an armature, a magnet having a plurality of polar extensions concentrated about said armature, each of said polar extensions being directly opposite a polar extension of opposite polarity, bevelled prongs at one extremity of said extensions for supporting an alternating current winding surrounding said armature, said prongs of said polar extensions being in spaced relation with said armature, said coil being located between polar extensions of opposite polarity on each side of said armature, and a contact device loosely engaging and electrically connecting a plurality of terminals, one of which is mounted on said armature, whereby upon the energization of said winding and the consequent vibration of said armature, said contact device is jostled, thereby breaking said electrical connection between the terminals.
6. A relay comprising a magnet, an alternating current winding in the magnetic field thereof, an armature, means for adjusting the effective vibrating length of said armature, a contact device loosely engaging and electrically connecting a series of terminals, being mounted on said armature, whereby upon the energization of said winding, and the consequent vibration of said armature, said contact device is jostled, thereby

breaking said electrical connection between the terminals.

7. A voice frequency relay comprising an armature, adjustment means for controlling the length of the vibrating portion thereof, the remaining portion being stiffened by said adjustment means and a rigid clamping support, circuit controlling means including a contact device loosely supported at each end by a terminal, one of which is mounted on said armature, and means comprising a coil adapted to be energized by a source of alternating current to cause said armature to vibrate in accordance with a desired frequency, to break said contacts.

8. An electromagnetic device comprising a magnet, a coil, an armature cooperating with said coil and magnet, said armature being adapted to be variably controlled to vibrate at a desired frequency, a contact device one end of which is loosely suspended from and makes electrical contact with a stationary terminal and the other end is loosely suspended from and makes electrical contact with a terminal mounted on said armature, whereby upon the energization of said coil, and the consequent vibration of said armature, motion is imparted to said contact device whereby said electrical contacts are broken.

9. An electromagnetic device comprising a magnet, an armature in the field of said magnet, an alternating current winding in operative relation to said armature, said magnet having a plurality of polar extensions of opposite polarity on each side of said armature, said polar extensions of like polarity being diagonally opposed to each other and positioned on opposite sides of said armature, said polar extensions containing slots for adjusting their space relation with said armature, and a loose contact device supported at one end from a stationary terminal and at the other end from a terminal mounted on and vibrating with said armature.

10. An electromagnetic device comprising a magnet, an armature in the field of said magnet, magnetic circuits including a portion of said armature as part thereof, means for energizing said magnetic circuits by alternating current whereby said armature may be caused to vibrate in accordance with the frequency of the applied current, and a loose contact device supported at one end from a stationary terminal and at the other end from a terminal mounted on and vibrating with said armature.

11. A relay comprising a magnet, an armature in the field of said magnet, magnetic circuits including a portion of said armature as part thereof, means for energizing said magnetic circuits by alternating current whereby said armature may be caused to vibrate in accordance with the frequency of said current, a loose contact device controlled by said armature, a stationary terminal on said armature, a second stationary terminal positioned in spaced relation to said armature, a support having a hook eye at the end thereof mounted on said second terminal, said contact device having a projection integral therewith loosely resting in an orifice of said first terminal, the other end of said contact device being a hook eye loosely linked to the eye of said support, whereby said contact device is coupled to vibrate in accordance with the frequency of said applied current without binding at its contacting extremities.

In witness whereof, I hereunto subscribe my name this 6th day of September A. D., 1924.

EDWARD J. PRATT.
